CLAIM

The ornamental design for a mount assembly, as shown and described.

DESCRIPTION

FIG. 1 is a right, front-side perspective view of a mount assembly.

FIG. 2 is a left, rear-side perspective view of the mount assembly of FIG. 1.

FIG. 3 is a front-side elevation view of the mount assembly of FIG. 1.

FIG. 4 is a rear-side elevation view of the mount assembly of FIG. 1.

FIG. 5 is a right-side elevation view of the mount assembly of FIG. 1.

FIG. 6 is a left-side elevation view of the mount assembly of FIG. 1.

FIG. 7 is a top plan view of the mount assembly of FIG. 1.

FIG. 8 is a bottom plan view of the mount assembly of FIG. 1; and,

FIG. 9 is a right, front-side perspective view of the mount assembly of FIG. 1 shown in a state of use.

The broken line showing of elements on the bottle or the mount assembly, where applicable, illustrate portions of the article and form no part of the claimed design.

1 Claim, 9 Drawing Sheets
